UNITED STATES PATENT OFFICE.

BASSETT JONES, OF MAHWAH, AND JAMES T. HOLMES, OF BOGOTA, NEW JERSEY.

SPARK INDICATOR AND AMPLIFIER.

Application filed March 12, 1920. Serial No. 365,267.

To all whom it may concern:

Be it known that we, BASSETT JONES and JAMES T. HOLMES, citizens of the United States, and residents of the village of Mahwah, county of Bergen, State of New Jersey, and town of Bogota, Bergen County, State of New Jersey, respectively, have jointly invented certain new and useful Improvements in Spark Indicators and Amplifiers, 5 of which the following is a description.

Our invention relates to spark producing apparatus.

It is well known that the larger the effective current through a spark gap, such as a 15 spark plug of an internal combustion engine, the hotter or "fatter" the spark and the better the results obtained from the engine.

We have found that in all of the wiring 20 arrangements between the timer and the spark plugs, a certain amount of inductance is present which, in many conditions, tends to reduce the effective current and hence the temperature of the spark. Moreover, it is 25 desirable that the person in charge of the apparatus be able to readily determine conditions in the branch circuits leading from the timer.

It is the principal object of our invention 30 to provide a device which shall serve as an indicator of conditions in the circuit in which it is connected and which shall also serve to increase the effective current in such circuit.

The novel features of our invention are 35 pointed out with particularity in the appended claims. The invention itself, however, with further objects and advantages, will best be understood from a perusal of the 40 following description taken in connection with the accompanying drawing, in which—

Fig. 1 is a perspective of the portion of 45 an automobile having our invention applied thereto, the ignition system of the automobile engine being indicated diagrammatically in this figure;

Fig. 2 is a vertical cross section through 50 a device embodying our invention of the kind appearing on the dash-board of the automobile in Fig. 1, and taken on the line 2—2 of Fig. 7;

Fig. 3 is a section on the line 3—3 of Fig. 2;

Fig. 4 is a perspective view of one of the 55 condenser plates in the device appearing

in Figs. 1, 2 and 3 and illustrating the arrangement of the spark points thereon;

Fig. 5 is a perspective view of one of the insulating blocks used between the plates in the device shown in Fig. 2; 60

Fig. 6 is a horizontal section taken on the line 6—6 of Fig. 7;

Fig. 7 is an elevational view of the device appearing in Figs. 1 and 2;

Fig. 8 is a sectional view of a modification embodying our invention, taken on the line 8—8 of Fig. 9, and 65

Fig. 9 is a sectional view of the device shown in Fig. 8, Fig. 9 being taken at right angles to Fig. 8. 70

Referring to the drawing more in detail, 1 is the dash-board of an automobile on which is fixed a box 2, containing a plurality of aligned spark-indicating and amplifying devices, such as 3, there being as many of the 75 individual devices 3 as there are spark plugs, such as 4, for the internal combustion engine of the automobile. A high tension magneto or other source of high tension current is indicated at 5, the circuit of the magneto 5 80 being grounded at 6 and connected to the moving arm 7 of the usual timer or distributor, which has fixed contacts, such as 8. Leading from the fixed contacts, 8, to the 85 spark plugs, 4, are branch circuits, such as 9, in each of which is connected any one of the devices, 3, according to our invention. Each of the devices 3 comprises two or more condenser plates, such as 10, each 90 two adjacent plates 10 being separated by insulating plates or disks, such as 11, of suitable dielectric material, the plates 10 and 11 being substantially the same dimensions in plan. The plates 11 are cut away at points in 95 their edges to form recesses, such as 12, and we provide tungsten spark points 13, preferably silver soldered to the plates 10, the points 13 projecting into the recesses 12 in the plates 11, but the points on adjacent plates being separated, as indicated at 14, 100 to provide spark gaps between the plates of the device. We prefer that the plates 10 and 11 be of cylindrical form so that when one or more sets of plates are assembled in one device, such as 3, they may be readily enclosed in a transparent insulating envelope, 105 such as 15, preferably of glass. The case or envelope 15 is preferably made open at each end and in assembling the ends of the cases are closed by caps, such as 16, of in- 110

sulating material. Suitable connections, such as 17, are provided that extend through apertures in the end caps 16 to enable the devices 3 to be connected into any circuit, 5 such as 9, in which it may be desired to use them. The spark gaps 14 are readily visible through the casing 15 so that any one can tell if the current in the circuit in which the device is used is of normal strength. The 10 observation of the spark gaps is facilitated by placing them adjacent to the casing 15, as shown in Fig. 2.

We prefer to enclose a plurality of devices, such as 3, within a box or casing, such 15 as 2, such box being provided with windows, such as 18, through which the action at the spark gaps 14 may be observed.

In Figs. 8 and 9, we have illustrated a device 3' according to our invention in which 20 the condenser plates 10' instead of being separated by disks or solid dielectric, as in the form shown in Fig. 2, are spaced at their edges by rings, such as 19, of transparent insulating material, such as glass, the plates 25 10' having spark points, such as 13', secured thereto in the same manner as in the case of the plates 10 and points 13. However, the majority of the portions of the surfaces of adjacent plates 10' being separated only by air, as a dielectric, spark points, such as 13', may be placed at any point on the surface of the plates 10' and in Figs. 8 and 9 they are shown as being placed at the centers of these plates.

35 In use, the individual indicators, such as 3 or 3', may be numbered according to the numbers of the cylinders of the engine or other circuit in which the device is used, and the sparking in the amplifiers or indicators 40 will indicate the order in which the spark plugs in the cylinders are working.

Should a cylinder begin to miss it will be observed at once that the sparking in the indicator for this cylinder has ceased and the 45 driver will know at once which cylinder is missing. He can also observe the sequence

in which it misses and this will tell him something of the reason for the missing and he will be able to go at once to the proper plug for investigation. This will be a particular advantage because frequently a cylinder will miss when the car is in motion and the engine doing work, but will cease to miss when the car has been stopped for the purpose of examining the spark plugs. 55

Should an open circuit occur in any of the wiring or leads it will be indicated at once by the cessation of the sparking in the indicator. If the open circuit is in the main leads to the timer, the sparking would 60 cease in all of the indicators.

Should a short-circuit occur in any of the leads it will be indicated at once by the fattening up of the spark in the indicator, for then the entire energy will be consumed 65 in the indicator.

It will be understood that while we have illustrated and specifically described our invention as being used in the ignition circuit of an internal combustion engine, that 70 our invention is not limited to such use.

Having thus described our invention, what we claim is:

1. A combined spark intensifier and indicator comprising in combination a condenser having plates and a solid dielectric between adjacent plates thereof, and visible spark points fixed to said adjacent plates and lying in the space defined by extensions of the surfaces of said dielectric in contact, 75 with said adjacent plates.

2. A combined spark indicator and intensifier comprising in combination a condenser having plates and a solid dielectric between adjacent plates thereof, said dielectric being cut away near the edges of said plates, and spark points fixed to said plates 85 lying in the space where said dielectric is cut away.

BASSETT JONES.
JAMES T. HOLMES.
